MODULATION

George L. Usselman, Port Jefferson, N. Y., assignor to Radio Corporation of America, a corporation of Delaware

Original application July 23, 1932, Serial No. 624,258, now Patent No. 2,075,071, dated March 30, 1937. Divided and this application October 1, 1935, Serial No. 43,013.

19 Claims. (Cl. 179—171)

The present invention relates to an improved method of and means for producing phase or amplitude modulated signals, or a combination of both, means for varying the phase or amplitude or both of radio waves or oscillations in accordance with the signals to be transmitted, and means for regulating during operation of the transmitter the amount of phase amplitude modulation or both accomplished. The present application is a division of my U. S. Appln. Ser. No. 624,258, filed July 23, 1932, Patent #2,075,071 dated March 30, 1937.

It has been discovered recently that most amplitude modulated transmitters have some phase modulation present in the signal. This in bad cases causes very objectionable distortion in the signal.

The present invention involves means heretofore unknown in the art for balancing out any phase modulation inherently produced in amplitude modulating a carrier wave at signal frequency.

It is also known that in accomplishing phase or frequency modulation of a carrier some amplitude modulation thereof is accomplished. This amplitude modulation results in distortion of the signal in the receiver.

The present invention involves means unknown heretofore in the art for balancing out any amplitude modulation or extraneous hum inherently produced in accomplishing phase modulation of a carrier.

In phase modulated transmitters, as disclosed in United States Appln. Ser. No. 602,487, filed April 1, 1932, Patent #2,049,143 dated July 28, 1936, and United States Appln. Ser. No. 607,932, filed April 28, 1932, Patent #2,036,164 dated March 31, 1936, phase modulation of a high frequency carrier in accordance with the signal to be transmitted has been accomplished.

In the first described application phase rotation of the carrier wave relative to the normal wave is accomplished by the use of a phase retarding inductance and phase advancing capacity in the grid circuits of the symmetrical modulator tubes.

In the second referred to application, phase modulation is accomplished by the use of lines of a different electrical length connecting the oscillation source substantially cophasally to the grids of a pair of tubes. One of the lines includes variable means, as, for example, a trombone tuning means.

In the above referred to applications in general the signal frequencies are applied to the

impedances of the tubes so that a phase shift, the amount of which is determined by the amplitude of the signal, appears in the energy repeated in the tubes and consequently appears in the output of the tubes.

In practice, it is often desirable to have a transmitter by means of which the degree of phase modulation effected in accordance with the signal may be varied during the operation of the transmitter so that signalling may continue during the adjustment of the degree of phase shift.

One of the main objects of the present invention is to provide a new and novel arrangement by means of which phase modulation may be accomplished and the degree of modulation may be varied during operation of the modulating means.

This is accomplished in accordance with the present invention by feeding unmodulated carrier energy to the tank circuit into which the phase modulated energy is fed and regulating the amount of unmodulated energy delivered to the tank circuit thereby regulating the degree to which the combined energy in the tank circuit is modulated in phase.

Under other conditions it is often desirable to transmit by means of the same transmitter phase modulated waves and amplitude modulated waves simultaneously so that two signals may be sent out at the same time, or to transmit either wave separately.

In its broadest aspect, this is accomplished by applying phase modulation to a carrier at signal frequency and amplitude modulations to the carrier at signal frequency simultaneously or separately, and feeding the combined energy or the energy from one of the modulators to a tank circuit, from which it may be utilized.

Another object of the present invention is to provide means whereby the hum and extraneous amplitude modulation, which may be inherently present in a phase modulator, may be corrected, compensated, or otherwise removed from the energy resulting from the phase modulation which is to be transmitted.

This last object is accomplished in accordance with the present invention by opposing, in the tank circuit, any amplitude modulation inherently accomplished by phase modulation of the carrier, with equal and opposite modulation components furnished by the amplitude modulator described briefly in the second preceding paragraph.

Conversely, the hum and extraneous phase

modulation which might be inherently produced by an amplitude modulator may, in accordance with the present invention, be opposed, by equal and opposite phase modulated components resulting from phase modulation of the carrier. In this arrangement, provision for varying the degree of phase modulation accomplished in the correction circuit, that is, the phase modulator, is desirable.

- 10 Where multiplexing of signals by the use of phase modulation and amplitude modulation is desired, the same carrier wave may be modulated in phase by one signal to be transmitted, and in amplitude by another signal to be transmitted, 15 or the same carrier may be modulated in phase and in amplitude by the same signal. Moreover, the phase or amplitude modulators above need not be used simultaneously but may be used separately.
- 20 The novel features of the invention have been pointed out with particularity in the claims appended hereto.

The nature of the invention and the mode of operation thereof, and the advantages to be gained thereby will be understood by the following description thereof and therefrom when read in connection with the drawings attached hereto throughout which like reference numerals indicate like parts, and in which:

- 25 Fig. 1 shows by way of illustration a phase and amplitude modulated transmitter which includes means by which the degree of phase modulation accomplished may be varied during operation of the transmitter and also means whereby the 30 transmitter may be arranged to operate as a phase modulator or as an amplitude modulator, or as a phase modulator and amplitude modulator for multiplex signalling; while

Figures 2 and 3 show arrangements wherein 35 means is provided for compensating the hum and extraneous phase modulation inherently produced in amplitude modulation of a carrier, and vice versa.

Referring to the drawings, and in particular 40 to Fig. 1 thereof, O indicates a high frequency oscillator of any known type such as a crystal oscillator which will produce oscillations of substantially constant frequency. The output of the oscillator O is connected, as shown, by way 45 of blocking condensers 1 and 2 to the inductance 3 of a tank circuit 4 including a tuning condenser 6 connected in parallel with the inductance 3. The upper terminal of the tank circuit 4 is connected as shown by way of blocking condenser 55 H and inductive reactance E to the grid 8 of a thermionic tube V₁ and by way of a capacitive reactance F to the grid 10 of a thermionic tube V₂. The lower terminal of the tank circuit 4 is connected by means of a blocking condenser 60 I and variable resistance G to the control electrode 12 of an additional thermionic tube V₃. The resistance G is preferably non-inductive. The high frequency input circuit of the tubes V₁, V₂ and V₃ is completed by way of a lead connecting a point on the inductance 4 to ground by way of capacity J₁.

70 Audio frequency signals from a source 14 are applied through transformer T₁ and resistances R₁ and R₂ respectively in phase opposition to the control electrodes 8 and 10 respectively of tubes V₁, V₂ respectively. The input circuit for the modulating signals is completed by a lead 16 connecting the center point of the secondary winding of transformer T₁ to a point on potentiometer P, which is in turn connected with the cath-

ode circuit 18 of tubes V₁, V₂. Filament heating potential is supplied from the battery 20 as indicated. Biasing potential for the control electrodes 8 and 10 of tubes V₁, V₂ respectively is supplied by way of lead 16 from potentiometer P connected across a portion of the battery 20.

The anode 22 of tube V₁ and anode 23 of tube V₂ are connected as shown to one terminal of a tank circuit 24 comprising an inductance 26 and variable capacity 27. Charging potential for the anodes 22 and 23 is supplied by way of a lead 28 connected between the battery 20 and a point on the inductance 26. Radio frequency oscillations appearing in this tank circuit are shunted around the source 20 by way of a bypass condenser 29.

The operation of this arrangement to accomplish phase modulation of the carrier supplied from O to the tubes V₁, V₂ in accordance with the signals supplied from 14 to said tubes has been described in considerable detail in the applications referred to hereinbefore. The operation thereof, however, will be repeated briefly here.

The high frequency oscillations supplied from O appear relatively displaced or shifted in phase on the control electrodes 8 and 10 of the tubes V₁, V₂ respectively. The shift in phase depends of course upon the values of the inductance L and capacity F inserted in the connections. Likewise, due to the repeating effect of the tubes V₁, V₂ the phase of the energy in the common tank circuit 24 will be advanced or retarded from the average phase position of the normal radio wave an angle, the sign of which depends upon which modulator tube is supplying the greater amount of power. The tube having lower instantaneous bias, which is in part, the result of the signal oscillations differently applied to the control electrodes thereof by way of transformer T₁, will, of course, have a greater controlling effect on the phase of the oscillations appearing in the common tank circuit 24. In effect, the phase of the oscillations appearing in the common tank circuit 24 will be advanced or retarded from the average phase position of the oscillations in a manner proportional to the controlling power of one modulator tube V₁ over the other modulator tube V₂. This controlling power of one modulator tube V₁ over the other modulator tube V₂ of course depends upon the effective bias applied to the control electrodes of the respective tubes. Since the secondary winding of transformer T₁ is energized by signal potentials the control electrode biasing excitation of the two phase modulator tubes will vary at signal frequency. The power supplied by each of tubes V₁, V₂ to the tank circuit will vary in accordance with the signal potential variations and therefore the repeated energy in the common tank circuit will be varied in phase as the signal frequency applied to the transformer varies and will have an instantaneous phase which depends upon the effective bias applied to the control electrode, which bias is determined by the constant fixed potentials applied thereto by way of lead 16 and the modulating potentials applied thereto from the secondary windings of transformer T₁.

The phase modulated energy appearing in the tank circuit 24 may be supplied to an amplifier 70 30 by way of blocking condensers 31 and 32. This amplifier may include frequency multiplying means and may be connected to an antenna system, as shown, from which the phase modulated energy may be radiated.

The means whereby amplitude modulations at signal frequency may be applied to the carrier from O will now be described.

The audio frequency source 14 has its output circuit connected by way of transformer T₂, switch K, and resistance R₃ to the control electrode 12 of tube V₃ so that when switch K is closed in the upper position modulating potentials are applied to the control electrode 12. This input circuit for the modulating potentials from 14 is completed by connecting the other terminal of the secondary winding of transformer T₂ to a tapped point on potentiometer P, which is in turn connected with the filament of tube V₂ by way of filament circuit 18. This tapped connection between the transformer winding and the potentiometer permits the value of the biasing potential applied to the grid 12 of V₃ to be regulated. The anode 33 of thermionic tube V₃ is connected, as shown, to the lower terminal of tank circuit 24.

Assuming that the transmitter is operating as described above to accomplish phase modulation of the carrier produced in O. If the switch K is closed (i. e., in the upper position) audio frequency oscillations are impressed from 14 upon the control electrode of tube V₃ and amplitude modulated wave energy appears in the tank circuit 24 connected with the anode 33 of tube V₃. These amplitude modulated oscillations are transferred along with the phase modulated signals to the amplifier 30 and radiated. The tank circuit 24 is normally tuned to the frequency of the tank circuit 4, both of these tank circuits being tuned to the frequency of the oscillations generated in O.

At the receiving station two receivers may be used or one receiver adapted to receive both audio frequency modulated waves and phase modulated waves and to separate the same. The carrier as transmitted by this arrangement has impressed thereon modulations in phase in accordance with the signals from source 14 and modulations in amplitude in accordance with signals from the source 14. Source 14 may be replaced by two sources as disclosed in my parent application Ser. No. 624,258 of July 23, 1932.

The amplitude modulator may be rendered inoperative by merely opening the switch K (down position) so that phase modulated signals only may be sent out.

In this arrangement any objectionable amplitude hum sometimes present in phase modulation transmission may be balanced out by applying potentials of a frequency equal to the frequency of the objectionable hum but opposite in phase so that the supplied potentials will oppose the objectionable hum. In other words, any amplitude modulation accomplished in the phase modulator part of the transmitter may be opposed in the tank circuit by amplitude modulation accomplished in V₃. By adjusting the direct current potential applied to the control electrode of tube V₃ or by adjusting the amplitude of the potentials supplied from 14 to V₃, the amplitude modulated signals applied from V₃ to the tank circuit 24 may be made equal in amplitude to the amplitude modulation inherently accomplished in the phase modulator part of the circuit and balance out the same so that pure phase modulated signals are fed from the tank circuit 24 to the amplifier 30. Compensating potentials of the proper frequency phase and amplitude may be produced in 14 or supplied thereto from any source.

Conversely, where it is desired to transmit amplitude modulated signals entirely free of any hum and extraneous phase modulation which is inherently accomplished in the amplitude modulator, the amplitude modulator tube V₃ may be energized to accomplish full amplitude modulation of the carrier from O and feed the amplitude modulated carrier to the tank circuit. 14 may then supply current of a frequency equal to the frequency of the undesired phase modulation accomplished in the amplitude modulator V₃. The phase relation of this alternating current produced in 14 or supplied by way of 14 to V₁ and V₂ should be so adjusted that the phase modulation produced in the phase modulator will oppose and compensate the phase modulation produced in the amplitude modulator. The degree of phase modulation accomplished in the phase modulators V₁ and V₂ may be regulated by adjusting the value of the phase retarding and advancing means E and F respectively and, further, by regulating the direct current bias applied to the control electrodes of the tubes V₁ and V₂ by way of resistances R₁ and R₂ respectively. Furthermore, the amount of current furnished by 14 to the phase modulator may be adjusted to a value such that the phase modulation components introduced into the tank circuit for correction purposes may be made equal and opposite to the undesired phase modulation components introduced into the tank circuit from the amplitude modulator.

The manner in which the degree of phase modulation accomplished may be varied or adjusted will now be described.

If the key K is moved to the lower position so that the secondary winding of T₂ is open at one end, no audio frequency signals from source 14 can be applied to the control electrode of tube V₃. Now, the amplification of this tube depends upon the bias applied to the control electrode thereof. If the negative bias on the amplitude modulator V₃ is set high, tube V₃ will supply only a small amount of unmodulated energy to the tank circuit 24 and the amount of phase modulated energy delivered to the tank circuit 24 from tubes V₁, V₂ will be relatively large. However, if the bias applied to the control electrode of the amplitude modulator V₃ is set low, that is, less negative, the amount of unmodulated energy delivered to the tank circuit 24 will be large and the amount of phase modulated energy delivered to the tank circuit 24 from tubes V₁, V₂ will be relatively small. The signal therefore in the first case will have a large degree of phase modulation while in the second case the signal will have a small degree of phase modulation. In both cases, the transmitter output power will be the same or can be made the same if a limiter is included in the amplifier 30, but the degree of phase modulation can be made different. This arrangement therefore permits the degree of modulation in phase applied to the carrier from O to be varied between certain limits. This variation of the degree of phase modulation may be accomplished during operation of the transmitter.

In order that the arrangement including the thermionic tubes V₁, V₂, V₃ may be balanced to some extent with respect to the tank circuit 4 the resistor G should be non-inductive and should be adjusted to equalize the load on both sides of the tank circuit, that is, since tank circuit 4 supplies the control electrodes of two tubes V₁, V₂ from one terminal and the control electrode of V₃ from the other.

only from the other terminal, some provision must be made to balance or equalize the load on this tank circuit. This resistor G permits this balance to be obtained.

5 In order to prevent the effects of coupling due to the inherent capacity of the electrodes in the tube from unbalancing the system, neutralizing condensers N₁, N₂ may be connected, as shown, between the terminals of the tank circuit 26 and the opposite terminals of the tank circuit 4.

10 Although, for purposes of illustration, I have shown my novel modulating circuits as including thermionic tubes of the three-electrode type, it will be understood that my invention is not limited to the use of any specific type of tubes since screen grid or multi-grid tubes may be used in place of the tubes shown. Furthermore, the use of such tubes in place of the tubes now shown in the present invention is thought to be within the 20 scope of the present invention. Where screen grid tubes are used in place of the triodes shown, neutralization of the tubes may not be necessary. Furthermore, where screen grid tubes are used the modulating potentials may be applied to the 25 screening grid electrode rather than to the control electrode, as shown. Where multi-grid tubes are used, appropriate changes may be made in the circuit to derive from the use of said tubes the optimum results.

30 Although, as indicated above, the arrangement of Fig. 1 may be operated primarily as an amplitude modulator, the phase modulator therein serving to furnish phase modulated energy to balance out any phase modulation inherently accomplished in the amplitude modulator, in many cases it is necessary to have better control or regulation of the compensating energy than may be obtained with the arrangement of Fig. 1.

35 In Fig. 2 is shown a preferred form of amplitude modulator means whereby the hum or extraneous phase modulation inherently accomplished in an amplitude modulator may be eliminated. In this arrangement audio frequency oscillations from the source 14 are supplied to an amplitude modulating potential amplifier 40. The amplifier 40 is connected with an intermediate amplifier 41 to modulate in amplitude the carrier frequency appearing therein from the source O by way of the phase modulator Q. The high frequency oscillations generated in O are impressed by way of a blocking condenser I, phase retarding means L, and amplitude regulating means R₂ to the control electrode 8 of tube V₁ and from the blocking condenser I by way of phase advancing means M to the control electrode 10 of tube V₂. These phase shifted oscillations produced as described in connection with Figure 1 are fed from the anodes 22 and 23 of tubes V₁ and V₂ respectively in parallel to the tank circuit 24 as in Fig. 1.

40 The tank circuit 24 is connected by way of blocking condensers 31 and 32 to the intermediate frequency amplifier 41. The audio frequency source 14 is also connected by way of a potentiometer P₁ and reversing switch S to the transformer T₁, the secondary winding of which is connected as shown to the control electrodes 8 and 10 of tubes V₁ and V₂ by way of resistances R₁ and R₂ respectively. In this manner audio frequency oscillations may be applied in phase opposition to 45 the control electrodes of tubes V₁ and V₂. The amplitude of the oscillations applied to the phase modulators V₁ and V₂ may be adjusted by adjusting the potentiometer P₁. The modulation potentials applied to the control electrodes of V₁ and V₂ 50 may be reversed in phase by the reversing switch

5 S. Energy for the filaments 18 of tubes V₁ and V₂ is supplied from a portion of direct current source 20, as in Fig. 1, while biasing potential for the control electrodes of tubes V₁ and V₂ is supplied by way of a connection 16 between a point on the 10 potentiometer P₂, connected in parallel with a portion of the source 20, and the secondary winding of transformer T₁. Charging potential for the anodes of tubes V₁ and V₂ is supplied by a lead 28 connecting the midpoint of the inductance 26 to the positive terminal of the source 20. Charging potential for the screen grid electrodes of tubes V₁ and V₂ is supplied by way of a lead 33 connecting said electrodes to a point on potentiometer P₃ connected in shunt with a portion of the source 20. 15 Radio frequency oscillations appearing in the input and output circuits and on the screen grid electrodes of tubes V₁ and V₂ are prevented from passing through the energizing source by bypassing condensers J₂, J₃, C connected as shown at 20 appropriate points.

The operation of the transmitter as illustrated in Fig. 2 is as follows:

To begin with, assume that no amplitude modulation is present that is, that the modulation amplifier in 40 is inoperative. High frequency oscillations are generated in the oscillator O. This high frequency energy is repeated in phase modulator Q, where it may be amplified or multiplied in frequency; when the oscillations are multiplied in 30 frequency, 24 is tuned to a harmonic of the frequency of O, or both. Modulator stage Q may also be followed by a frequency multiplier or multipliers not shown. The high frequency oscillations are repeated in stages 41 and 43, where they 35 receive further amplification. The oscillations amplified in stage 43 are delivered to the antenna F, where they are radiated.

Now, if audio signals are produced or amplified in 14, they will be transmitted to the modulation 40 amplifier stage 40, which in turn modulates in any well known manner the amplitude of the radio frequency energy in 41. The amplitude modulated signals or oscillations from intermediate amplifier 41 are repeated and amplified in 43 and 45 transferred from 42 to the antenna F.

If in accomplishing the amplitude modulation in unit 41 no phase modulation has been caused, the movable point on potentiometer P₁ should be moved to zero position so that no audio frequency 50 is applied to the control electrodes of tubes V₁, V₂ of this phase modulation stage. The phase modulator Q will act as a straight amplifier or frequency multiplier of the oscillations impressed from O. However, if phase modulation is produced in the process of amplitude modulation in 41, the procedure of eliminating it is as follows: P₁ is adjusted so that audio frequency oscillations from 14 are applied to the control electrodes of tubes V₁, V₂, the carrier energy supplied from O by 60 way of phase modulators V₁, V₂ to the intermediate amplifier 41 will be modulated in phase at the frequency of the oscillations from source 14. The reversing switch S should be put in the position which will cause the phase modulation produced 65 in the tubes V₁, V₂ to oppose the phase modulation inherently produced in the amplitude modulator stages. After this has been done, potentiometer P₁ may be adjusted until the phase modulation in the radiated signal is just balanced out.

Often the audio frequency potentials supplied from source 14 by way of switch S are not of the proper phase to produce in the tank circuit 24 and following stages compensating potentials which oppose by 180 degrees the undesired phase 75

modulations inadvertently produced in amplitude modulating the carrier in 41. For example, if when the switch S is closed in one position to furnish compensating phase modulations and 5 a 45 degree phase relation exists between the phase modulation furnished from V₁, V₂ and the undesired phase modulations accomplished in the amplitude modulator, reversing the position of the switch S would merely shift the phase angle 10 of the compensating energy to a different quadrant but still would not oppose the energies, that is, make them 180 degrees apart.

In order to insure complete compensation of 15 the undesired phase modulations produced in the amplitude modulator I provide a phase adjusting means 44 inserted as shown in the modulating potential leads between the source 14 and the modulation amplifier 40. This phase adjusting means permits the modulating potentials 20 fed to the unit 40 to be adjusted to such a value that the phase modulation accomplished in 41 is exactly opposed by the compensating phase modulations produced in V₁, V₃.

The device of Fig. 3 is in the main similar in 25 arrangement and operation to the device of Figure 2. In the arrangement of Fig. 3, however, the audio frequency phase adjusting means 44 is interposed between the source 14 and the potentiometer P₁. Here, as in Fig. 2, the rough 30 adjustment to oppose the undesired phase modulations produced in the amplitude modulator by phase modulations from the phase modulation stage is accomplished by the reversing switch S while the more exact opposing adjustment is accomplished by the use of the phase adjusting 35 means 44.

If in the devices of Figs. 2 and 3 the undesired 40 phase modulation in the signal is caused by oscillations of a frequency other than the frequency of the signal from 14, it is only necessary to introduce energy of this undesired frequency into the input circuit of phase modulators V₁, V₂ and by making the proper adjustments this undesired 45 frequency will be eliminated from the radiated signals.

While applicant has used three electrode tubes to illustrate the novel system of Fig. 1, it will be understood that the invention is not to be limited thereby since applicant contemplates the use of 50 any tubes known in the art in these systems. Likewise, the use of screen grid electrodes in Figs. 2 and 3 is not intended to limit applicant to the use of such tubes since, obviously, three electrode tubes may be used in place of the tubes shown. 55 When three electrode tubes are used the system may be neutralized in a manner as illustrated in Fig. 1. Furthermore, the use of such tubes and the changes in the circuits necessary to derive the best results are within the scope of the present invention.

What is claimed is:

1. The combination, with an amplitude modulator comprising a modulator tube connected to a source of carrier frequency oscillations and a 60 source of modulating potentials and an output circuit, of means for compensating any phase modulation inherently accomplished in said amplitude modulator including, a pair of thermionic tubes each having an anode, a cathode and a 65 control grid, a connection between the anodes of said tubes and said modulator tube, circuits connecting the control grids of said tubes through phase shifting elements of different character to said 70 source of carrier frequency oscillations, said 75 pair of tubes being in said connection between

said source of carrier frequency oscillations and said modulator tube, circuits connecting the grid to cathode impedances of said tubes in phase opposition to said source of modulating potentials connected with said amplitude modulator whereby phase modulation of said carrier frequency oscillations in accordance with said modulating potentials is accomplished in said tubes and circuits, and impressed on said amplitude modulator whereby the phase modulation inherently produced by said amplitude modulator is opposed and compensated by said other phase modulation. 5

2. Signalling means including, a work circuit, a source of high frequency oscillations, an amplitude modulator tube having an anode, a cathode and a control grid, a connection between said control grid and said source of high frequency oscillations, a single source of signal potentials, means for applying potentials from said source of signal potentials to the control grid of said tube to produce amplitude modulation of said high frequency oscillations appearing in said work circuit, and means for balancing out any phase modulation accomplished in said amplitude modulator tube comprising, a pair of thermionic tubes each having anode, cathode and control electrodes, circuits connecting the control electrodes of said pair of tubes through phase shifting devices of different character to said source of high frequency oscillations, circuits 20 connecting the control electrodes of said tubes in phase opposition to said single source of signal potentials whereby compensating phase modulation of said high frequency oscillations in accordance with said signal potentials is accomplished in said pair of tubes and circuits, and means for impressing said last named phase modulation on said amplitude modulation to oppose and compensate said inherent phase modulation including circuits connecting the anode 25 electrodes of said pair of tubes to said work circuit. 30

3. In a signalling system, a source of wave energy, a modulator, means for impressing wave energy to be modulated thereon, a load circuit coupled to said modulator, a source of modulating potentials, and an amplifier coupling said source of modulating potentials to said modulator to amplitude modulate carrier wave energy therein, said wave impressing means including 45 means for compensating hum or extraneous phase modulation inherently accomplished in said amplitude modulator comprising a pair of thermionic tubes each having electrodes including a cathode, a control grid and an output electrode, reactances 50 of different character connecting the control grids of said tubes to said source of wave energy, a circuit coupling said source of modulating potentials in phase opposition to like electrodes in said tubes and means coupling the output electrodes of said tubes to said amplitude modulator, whereby compensatory phase modulation of said wave energy is produced in said tubes and said wave energy so modulated is impressed on said amplitude modulator wherein said phase modulations oppose and compensate said inherent hum or extraneous phase modulation. 55

4. A system as recited in claim 3 in which said last named circuit includes a reversing switch to reverse the polarity of said source of modulating potential relative to the said like electrodes of said tubes. 60

5. A system as recited in claim 3 in which said last named circuit includes potentiometer means for controlling the amplitude of the modulating 75

- potentials applied from said source to the said like electrodes of said tubes.
6. A system as recited in claim 3 wherein said load circuit is tuned to a harmonic of the frequency of said source of wave energy.
7. A system as recited in claim 3 wherein said amplifier is also a frequency multiplier.
8. A system as recited in claim 3 in which phase adjusting means is interposed in said last named circuit to control the phase of the modulating potentials applied to said like electrodes.
9. A system as recited in claim 3 in which said like electrodes are the control grids of said tubes.
10. A system as recited in claim 3 in which phase adjusting means is interposed between said source of modulating potentials and said amplifier to control the phase of the modulating potentials impressed from said source on said amplifier.
11. A system as recited in claim 3 wherein a wave amplitude regulating resistance is connected in series with one of said reactances of different character connecting the control grids of said tubes to said source of wave energy.
12. In a signalling system, a source of oscillatory energy of carrier wave frequency, a source of modulating potentials, a work circuit, a relay stage having an output connected to said work circuit, said relay stage having an input, a pair of tubes having input electrodes and having output electrodes coupled to said relay stage, circuits connecting the input electrodes of said tubes to both of said sources whereby the phase of said oscillatory energy is modulated in said tubes in accordance with said modulating potentials, means in said last named circuits for controlling the degree of said modulation, means for modulating in amplitude the input to said relay stage comprising an amplifier having controlling electrodes coupled to said source of modulating potentials and output electrodes coupled to said relay stage, and means connected with said source of modulating potentials to adjust the phase of the modulating potentials supplied to one of said modulators.
13. In a signalling system, a work circuit, an oscillatory energy amplifier having an input and having an output coupled to said work circuit, a source of high frequency oscillatory energy, a source of modulating potentials, a pair of relay tubes each having a control grid, a cathode, and an anode, phase shifting reactances of different character connecting the control grids of said tubes to said source of oscillatory energy, a tunable circuit connecting the anodes of said tubes together and to the input of said oscillatory energy amplifier, a modulating potential impedance connected between the control grids of said tubes, a circuit including potential reversing means coupling said impedance to said source of modulating potentials, said arrangement being such as to produce phase modulation of said oscillatory energy in accordance with said modulating potentials, and means for modulating in amplitude the input to said amplifier comprising an additional amplifier having controlling electrodes coupled to said source of modulating potentials and output electrodes coupled to said oscillator energy amplifier to modify therein said phase modulated oscillatory energy.
14. A signalling system as recited in claim 13 wherein phase and amplitude adjusting means is interposed in said coupling between said impedance and said source of modulating potentials.
15. A signalling system as recited in claim 13, wherein amplitude regulating means is interposed between said impedance and said source of modulating potentials and wherein phase adjusting means is interposed between said source of modulating potentials and the input of said amplitude modulator.
16. In signalling apparatus, a source of carrier wave energy, a single source of modulating potentials, an amplitude modulator connected to said source of carrier wave energy, a circuit connecting said amplitude modulator to said source of modulating potentials, an output circuit connected with said amplitude modulator and means for balancing out any phase modulation inherently accomplished in said amplitude modulator comprising a phase modulator connected to said source of wave energy, a circuit connecting said phase modulator to said source of modulating potentials, and phase adjusting means in one of said circuits.
17. In signalling apparatus, the combination of a source of carrier wave energy, a single source of modulating potentials, a phase modulator connected to said source of carrier wave energy and to an output circuit, a circuit connecting said phase modulator to said source of modulating potentials, and a device for balancing out any amplitude modulation inherently accomplished in said phase modulator comprising an amplitude modulator connected to said phase modulator, a circuit connecting said amplitude modulator to said source of modulating potentials, and phase adjusting means in one of said circuits.
18. A system as recited in claim 16 wherein one of said circuits also includes phase reversing means.
19. A system as recited in claim 17 wherein one of said circuits also includes phase reversing means.

GEORGE L. USSELMAN.
